UNITED STATES PATENT OFFICE

91,168

DESIGN FOR A COMBINED BUREAU AND MIRROR

Fred Geibelt and Charles Beeston, New York,
N. Y.

Application July 1, 1933. Serial No. 48,623

Term of patent 3½ years

To all whom it may concern:

Be it known that we, FRED GEIBELT and CHARLES BEESTON, citizens of the United States, residing in the city of New York, N. Y., have invented a new, original, and ornamental Design for a Combined Bureau and Mirror, of which the following is a specification, reference being had to the accompanying drawing, forming part thereof.

The figure is a perspective view of the combined bureau and mirror, showing our new design.

We claim:

The ornamental design for a combined bureau and mirror as shown.

FRED GEIBELT.
CHARLES BEESTON.
